(57) **CLAIM**

The ornamental design for a cannabis smoking article and packaging, as shown and described.

DESCRIPTION

FIG. 1 is a perspective view of the cannabis smoking article and packaging showing my new design,
 FIG. 2 is another perspective view thereof, shown one of the individual package is detached;
 FIG. 3 is a front elevated view thereof;
 FIG. 4 is another perspective view, showing one of the individual package for ease of illustration; and,
 FIG. 5 is a back perspective view, showing one of the individual package for ease of illustration.
 The regular dash lines are included for the purpose of illustrating the perforation between each packaging of the cannabis smoking article and packaging, and is claimed. The remaining broken lines of the cannabis smoking article and packaging form no part of the claimed design.
